UNITED STATES PATENT OFFICE.

ERNEST MOONEY, OF YORK, ENGLAND.

LUBRICATING DEVICE FOR RAILWAY VEHICLE AXLES.

Application filed April 13, 1923. Serial No. 269,828.

This invention relates to that kind of railway axle lubricating device in which an absorbent pad connected to or formed integral with capillary feeders dipping into the oil 5 in the axle-box is supported in contact with the journal by means of a spring frame comprising a cradle, a transverse bearer strip central to the cradle, straight longitudinal side members connected together by transverse strips, and double elliptical side members attached to the longitudinal side members and to the ends of the transverse bearer strip.

Now the chief object of the present invention is to prevent waste of lubricating oil as a result of splashing, and a further object is to provide for the lubrication of the boss of the wheel carried by the axle journal.

According to the invention, the capillary feeders of the absorbent pad pass through a sheet of absorbent material located over the oil in the bottom of the axle-box. To ensure of lubrication of the wheel boss, the spring frame carries auxiliary pads in contact with the wheel boss and having capillary feeders which pass through the sheet of absorbent material into the oil contained in the bottom of the axle box.

In order that the invention may be clearly understood and readily carried into effect, the same will now be more fully described with reference to and by the aid of the accompanying drawings; wherein:—

Figure 1 is an end elevation of my improved 35 lubricating device, with the axle box shown in section.

Figure 2 is a sectional side elevation of Figure 1.

Referring to the drawings, 1 is the absorbent pad formed integral with capillary feeders 2 which dip into the oil 3 in the lower part of the axle-box 4, said absorbent pad 1 being supported by means of a spring frame comprising a cradle 5, a transverse bearer strip 6 central to the cradle 5, straight longitudinal side members 7 connected together by transverse strips 8, and double elliptical side members 9 attached to the straight longitudinal side members 7 and to the ends of the 50 transverse bearer strip 6.

The lubricating device as a whole is supported in position upon a ledge 10 projecting inwardly from the walls of the axle-box 4, and the capillary feeders 2 of the absorbent pad 55 1 pass through a sheet of material 11 which extends the full width and length of the lu-

bricating device and is secured to the underside thereof in any appropriate manner. Thus any oil which splashes up is absorbed by the sheet of absorbent material 11, and is utilized to feed the absorbent pad 1 by way of the capillary feeders 2 which pass through said absorbent sheet 10.

One of the transverse strips 8 which connect the ends of the longitudinal side members 7 has mounted thereon brackets 12 carrying at their upper or outer ends auxiliary absorbent pads 13 projecting through holes 14 in the adjacent wall of the axle-box 4 and contacting with the wheel boss 15 carried by the journal 16 against which the absorbent pad 1 is supported by its spring frame, and such auxiliary pads 13 also have capillary feeders 2 which pass through the sheet of absorbent material 11 and dip into the oil 3 in the lower part of the axle-box 4.

I claim:—

1. In a lubricating device of the class described, an absorbent pad, capillary feeders formed integral with said absorbent pad, a spring frame supporting said pad in contact with the axle journal, a sheet of absorbent material located over the oil in the axle-box and through which said capillary feeders pass into said oil, and auxiliary absorbent pads carried by the spring frame and having capillary feeders also passing through the said sheet of absorbent material into the oil in the axle-box, said auxiliary absorbent pads contacting with the wheel boss carried by said axle journal.

2. In a lubricating device of the class described, a spring frame comprising a cradle, a transverse bearer strip central to the cradle, straight longitudinal side members, transverse strips connecting said longitudinal side members, double elliptical side members attached to the longitudinal side members and to the ends of the transverse bearer strip, and brackets mounted on one of the transverse strips, an absorbent pad carried by said cradle, capillary feeders formed integral with said absorbent pad, a sheet of absorbent material through which said capillary feeders pass into the oil in the axle-box and below said sheet of absorbent material, auxiliary absorbent pads carried by said brackets and having capillary feeders also passing through said sheet of absorbent material into the oil in the axle-box.

ERNEST MOONEY.
